UNITED STATES PATENT OFFICE.

FRANK DURANTE, OF PATERSON, NEW JERSEY.

CARBURETOR.

Application filed August 18, 1923. Serial No. 658,038.

To all whom it may concern:

Be it known that I, FRANK DURANTE, a subject of the King of Italy, residing at Paterson, in the county of Passaic and 5 State of New Jersey, have invented certain new and useful Improvements in Carburetors, of which the following is a specification.

This invention relates to carburetors of 10 the type in which there is a gate arranged to move across the passage in which the mixing of the air and fuel is effected and an inlet for fuel delivering into the passage at the side thereof toward which the gate 15 moves in closing. The object of the invention is to produce in a simple form of carburetor improved carburetion at all speeds including idling and also on starting.

In the accompanying drawings,

20 Fig. 1 is a view showing the improved carburetor in a vertical section taken centrally through the mixing passage and float chamber;

25 Fig. 2 is a plan, partly in section;

Fig. 3 is a side elevation of the valve structure, partly broken away;

Fig. 4 is a fragmentary section on line 4—4, Fig. 1;

30 Fig. 5 is a side elevation, partly in central vertical section, of a modified form of the carburetor; and

Fig. 6 is a section on line 6—6, of Fig. 5.

The mixing passage *a* of the improved carburetor is afforded by a vertical tube *b* 35 having a flange *c* at the top whereby to secure the carburetor to the intake manifold *d* of an engine and having at its lower end the lateral tubular portion *e* affording the intake opening *e'* to or laterally extending 40 part of the passage *a*. *f* is the float chamber which is here shown integral with the tube *b* and which contains a float *g* pivotally connected with one end of a lever *h* fulcrumed between its ends in the float 45 chamber and having its other end supporting a push-pin *i* sliding vertically in a port *j* at the top of the float chamber and provided with a valve seat *k* for a downwardly spring-held ball-valve *l*. When the level 50 of the fuel *m* in the chamber *f* falls the float descends and through the push-pin opens the valve *l* to admit the fuel through port *j* from any suitable supply, and when the fuel thus accumulates in the chamber 55 the float rises and allows the ball-valve to re-seat to check the further admission of

fuel to the chamber, all as will be obvious.

A sleeve valve *n* is guided by and slides vertically in the tube *b* forming in part the mixing passage. It is open at the top and 60 its lower end is cut to a plane at right angles to its longitudinal axis, being adapted when the valve is fully depressed to seat squarely on the flat surface *a'* of the horizontally extending wall at the bottom of 65 the passage. The portion *n'* of this valve which covers or closes off the opening *e'* at this time constitutes in effect a sliding gate. The valve is manually raised and lowered by the operator through the medium of a lever *o* suitably fulcrumed in the tube *b* and connected by a link *p* with an arm *r* which extends down into and is secured to the gate portion *n'* of the valve by a screw *s*.

75 A vertical hole forming a fuel inlet *t* is formed in the carburetor structure so that it discharges upwardly through the wall which affords the surface formed by *a'* and the bottom of the opening *e'*, it being connected with the float chamber by a horizontal port *u* and having at its lower end a drain valve *v*. In the inlet *t* is slideable vertically a spindle forming a valve *w* snugly fitting the inlet. This 80 valve is affixed at its upper end to the valve *n* by the screw *s*, so that the two valves move as one, that is, vertically, or transversely of the direction of flow of the air through the opening *e'*. The valve *w* is longitudinally 85 grooved, and in the preferred construction there are two such grooves, *w'*, and they are arranged laterally in the valve with respect to the direction in which the air flows 90 through the opening *e'*; each groove tapers upwardly as shown best in Fig. 1. The 95 grooves lie in a vertical plane close to that of the gate *n'* and preferably outward thereof.

100 For the purpose of starting the engine and for idling, at which time the valve structure *n*—*w* is preferably fully depressed, a port *x* for fuel is formed by a channel in and extending longitudinally of the valve 105 *w* at the side thereof nearest the mixing passage and another port *y* for air extends through the overlapping portions of the valves *n* and *w*.

110 The construction of Figs. 5 and 6 is identical to that already described excepting that the provision for supplying fuel and

air for starting and idling includes a port z leading from the surface a' downwardly and a port 2 for fuel leading from port z downwardly to duct u and a port 3 for air 5 leading from port z to the atmosphere, the quantity of fluid supplied by port z to the mixing passage being regulated by a screw valve 4 .

The speed of the engine is of course varied 10 by raising or lowering the valve structure $n-w$, the grooves w' due to their taper varying the quantity of fuel released, as the air-valve varies the amount of air admitted to the mixing passage. At all times the 15 valve w is subject to the cooling influence of the atmosphere, which thus resists its undue expansion due to heat imparted thereto by the air (in case the frequent practice of pre-heating the air is followed), so that it may have a closer fit. Especially in idling, and to a more or less extent in any but the fully open position of valve n , a good 20 preliminary mixing of the fuel and air ensues because fuel inlet t is placed near the plane of the gate n' and at the side of opening e' to which the gate approaches in closing, i. e., so that it will deliver into the air-stream where the latter's velocity is greatest. The good carburetion which is thus 25 insured is further enhanced by arranging the grooves w' in the valve w laterally thereof with respect to the path of flow of the air, so that the air displaces the fuel in a more comminuted form than would be possible if 30 the grooves were in the portions of the valve facing lengthwise of said path, in which case the fuel seems to collect in more or less large globules before the air acts to remove it.

35 40 Having thus fully described my invention, what I claim as new and desire to secure by Letters Patent is:—

1. A carburetor having a mixing passage

formed with a laterally extending air-intake portion and having an outlet for the mixture of air and fuel, a sleeve-valve slidable in and lengthwise of the passage and having a portion thereof forming a thin-walled gate movable across said intake portion, the carburetor having a bottom wall forming 45 the lower side of said intake portion toward and close to which the valve moves to restrict the flow through said intake portion and said bottom wall having a fuel inlet to 50 said mixing passage arranged relatively exterior of the valve and in close proximity to the plane of movement of the gate, and a fuel-flow-controlling valve movable in 55 said fuel inlet and attached to the sleeve-valve to move therewith, said sleeve-valve 60 affording communication through itself from the intake-portion to the mixture outlet.

2. A carburetor having a mixing passage provided with an air intake and an outlet 65 for the mixture of air and fuel, a fuel inlet entering said passage laterally thereof, a valve slidable back and forth across the passage toward the side thereof occupied by 70 said fuel inlet and arranged as an entirety between said fuel inlet and mixture outlet and in close proximity to the former and having a passage through itself extending lengthwise of its path of sliding movement and being also thin-walled, and a fuel-flow- 75 controlling valve movable in said fuel inlet and attached to the first valve to move therewith, the structure formed by said valves having a port for fluid flow through itself from the intake to the discharge side of 80 said structure and arranged to be near said side of the mixing passage when the first valve is closed.

In testimony whereof I affix my signature.

FRANK DURANTE.
